Inventor:

Robert Friedlander,

by Robert Burns
Attorney.

UNITED STATES PATENT OFFICE.

ROBERT FRIEDLANDER, OF CHICAGO, ILLINOIS.

X-RAY TUBE.

SPECIFICATION forming part of Letters Patent No. 777,503, dated December 13, 1904.

Application filed September 12, 1904. Serial No. 224,073. (No model.)

To all whom it may concern:

Be it known that I, ROBERT FRIEDLANDER, a citizen of the United States of America, and a resident of Chicago, in the county of Cook and State of Illinois, have invented certain new and useful Improvements in X-Ray Tubes, of which the following is a specification.

This invention relates to that type of vacuum or X-ray tubes in which provision is made for regulating the degree of vacuum existing within the tube, and more especially to that form of such tubes which forms the subject-matter of Letters Patent No. 725,331, issued April 14, 1903, to Theodor Friedlander; and the present improvement has for its object to provide a simple and efficient structural arrangement and combination of parts whereby the degree of attenuation within the ray-tube can be increased or diminished as required and as will hereinafter more fully appear.

The accompanying drawing represents a side elevation, partly in section, of an ordinary X-ray tube to which the present invention is applied.

Referring to the drawing, 1 represents the ray-tube body, in extensions of which the cathode head or terminal 2 and main and supplementary anode heads or terminals 3 and 4 are arranged as shown or in any other usual and suitable manner.

5 is a tubular neck or chamber connecting with the ray-tube proper, so as to be in communication with the interior of the ray-tube.

6 is a head or terminal arranged in the interior of the neck or chamber 5 and provided with the usual connecting-eye 7 of the exterior of the neck 5 for convenient connection with the line wire or wires of the inductorium.

40 In the present invention the head or terminal 6 constitutes the means for effecting an increase or a decrease, as required, in the degree of attenuation of the atmosphere within the ray-tube, and to such end has a compound construction, as follows:

8 is tubular casing or shell forming a portion of the head or terminal 6 aforesaid, and formed of platinum or other equivalent material, which under the influence of an elec-

trical discharge from the positive pole of an inductorium is adapted to absorb in a gradual manner portions of the attenuated gaseous atmosphere of the ray-tube to effect a gradual increase in the degree of attenuation of the same.

9 is a mass or filling within the interior of the casing 8 aforesaid. Such mass is composed of potassic hydrate or other like substance, which under the influence of an electrical discharge from the negative pole of the inductorium is adapted to give off in a gradual manner a volume of gas to the gaseous atmosphere of the ray-tube to effect a gradual decrease in the degree of attenuation of the same.

10 is a passage in the side of the tubular casing or shell 8, through which the gas generated from the filling 9 passes into the interior of the ray-tube.

Various ordinary modifications can be made in the relative arrangement and formation of the parts constituting the terminal or head 6 without departing from the scope of the present invention so long as the essential feature of the invention is maintained, and which consists, broadly, in having the parts 8 and 9 connected in common to a single external connecting-eye or its equivalent and adapted for connection with one or the other of the poles of an inductorium or other source of high-frequency electric current.

The present invention affords a very simple, durable, and efficient arrangement of parts, wherein a single connecting-eye 7 is capable of energizing either of the aforesaid increasing and reducing agencies 8 and 9 to either increase or reduce the degree of alteration of the atmosphere of the ray-tube, the only requirement being a change in the connection from the positive to the negative current, or vice versa, of the inductorium to the aforesaid eye 7 or a complete disconnection of the inductorium from such connecting-eye when the required degree of attenuation is attained.

Having thus fully described my said invention, what I claim as new, and desire to secure by Letters Patent, is—

1. A ray-tube, and a compound terminal ar-

ranged therein and comprising a gas-absorbing and a gas-evolving element, substantially as set forth.

2. A ray-tube, and a compound terminal arranged therein and comprising a shell of gas-absorbing material and a mass of gas-evolving material inclosed in said shell, substantially as set forth.

3. A ray-tube, a compound terminal arranged therein and comprising a gas-absorbing and a gas-evolving element, and an external electrical connecting means common to both of said elements, substantially as set forth.

4. A ray-tube, a compound terminal arranged therein and comprising a shell of gas-absorbing material and a mass of gas-evolving material inclosed in said shell, and an external electrical connecting means common to both of said gas-absorbing and gas-producing materials, substantially as set forth.

5. The combination of a ray-tube having anode and cathode terminals, and a compound terminal arranged therein and comprising a gas-absorbing and a gas-evolving element, substantially as set forth.

25 6. The combination of a ray-tube having

anode and cathode terminals, and a compound terminal arranged therein and comprising a shell of gas-absorbing material and a mass of gas-evolving material inclosed in said shell, substantially as set forth.

7. The combination of a ray-tube having anode and cathode terminals, a compound terminal arranged therein and comprising a gas-absorbing and a gas-evolving element, and an external electrical connecting means common to both of said elements, substantially as set forth.

8. The combination of a ray-tube having anode and cathode terminals, a compound terminal arranged therein and comprising a shell of gas-absorbing material and a mass of gas-evolving material inclosed in said shell, and an external electrical connecting means common to both of said gas-absorbing and gas-producing materials, substantially as set forth.

Signed at Chicago, Illinois, this 6th day of September, 1904.

ROBERT FRIEDLANDER.
